UNITED STATES PATENT OFFICE

2,457,943

ROCKER ARM CONSTRUCTION

Jesse G. Vincent, Grosse Pointe, Mich., assignor to
 Packard Motor Car Company, Detroit, Mich., a
 corporation of Michigan

Application November 13, 1945, Serial No. 628,018

10 Claims. (Cl. 74—519)

1

The invention relates generally to multicylinder internal combustion engines and more particularly to a rocker arm construction therefor.

In a "Rolls-Royce" engine of the type now employed in airplanes and having the cylinders arranged in a line, the rocker arms for operating the intake and exhaust valves are located over the cylinders. The entire engine is compactly designed, and because of such compactness the rocker arms for the intake and exhaust valves of each cylinder are nested together to occupy a minimum of space.

The rocker arms are operated by cams on a shaft extending lengthwise of and over the cylinder head casting, and such cams are constructed to provide a fairly large throw. Each cam therefore has a steep rise. The rocker arms heretofore used have had a sliding or rubbing contact with the cams, which, with the steep rise of the cam, resulted in undue wear on the rocker arm. To eliminate such wear, a roller mounted on the rocker arm may be employed, the roller thus providing a rolling contact instead of a rubbing contact. However, in attempting to mount a suitable roller on the rocker arm, difficulty is encountered because of the nested arrangement of the arms. The arm itself requires some enlargement to provide space for the roller and at the same time maintain sufficient strength in the arm. The roller also has to be adequately supported in the arm by means such as a pin or axle, and such pin must be retained in the rocker arm in fixed relation thereto without materially increasing the overall dimensions of the arm.

The general object of the invention is therefore to provide a novel rocker arm construction provided with a cam-engaging roller supported in the arm in such a manner that the over-all dimensions of the arm are not materially increased over the dimensions of the prior rollerless arm, so that the present arm may be substituted for the prior type without altering any other portions of the engine.

More specifically, it is an object to provide a rocker arm construction provided with a cam-engaging roller supported in the arm by a pin or axle which is headless so as not to project beyond the side faces of the arm and which is so secured in the arm as to be rigidly retained therein without danger of shifting or loosening during operation of the engine.

Another object is to provide a novel rocker arm construction provided with a cam-engaging roller, the mounting for which comprises parts which may be readily manufactured and assembled.

2

A further object is to provide a novel rocker arm construction provided with a cam-engaging roller carried by a pin or axle rigidly retained in the arm and providing for adequate lubrication of the bearing for the roller.

Other objects and advantages will become apparent from the following description taken in connection with the accompanying drawings, in which:

10 Figure 1 is a fragmentary view of a portion of an engine provided with rocker arms embodying the features of the invention.

Fig. 2 is an enlarged sectional view taken on the line 2—2 of Fig. 1.

15 Fig. 3 is a sectional view taken on the line 3—3 of Fig. 1.

Fig. 4 is a sectional view taken on the line 4—4 of Fig. 3.

In Fig. 1, I have illustrated a portion of an internal combustion engine of the type herein contemplated, and in this figure there is shown a cylinder head 10 provided with a plurality of brackets 11 supporting a camshaft 12 and a pair of rocker arm supporting shafts 13. The camshaft 12 is mounted directly over the ends of the cylinders, while the rocker arm supporting shafts 13 are equally spaced from and are on opposite sides of the camshaft 12, the rocker arm shafts 13 being positioned below the camshaft 12 to provide a triangular arrangement therewith, as is apparent in Fig. 3. Carried by the shafts 13 are a plurality of rocker arms, indicated generally at 14, the rocker arms being arranged in pairs respectively mounted on the two shafts 13 and extending toward each other in an overlapping relation to actuate valves in the cylinder head 10, the rocker arms being operated by cams 15 provided on the camshaft 12 and overlying the rocker arms 14.

40 The engine herein partially shown is compactly designed to occupy a minimum of space. As an incident to such compactness, the rocker arms 14 are nested together in pairs, as is apparent from an inspection of Figs. 1 and 4. The cams 15 in an engine of this type have a fairly large throw and therefore each cam has a steep rise or ramp forming the lobe of the cam. Heretofore, rocker arms have been so constructed as to have a rubbing contact with the cams and, because of such steep rise, the rubbing action produced undue wear on the rocker arms. Much of such wear can be eliminated by providing a roller on each rocker arm to contact with the cam so that a rolling contact would thereby be substituted for the rubbing action. However, because of the nested arrange-

ment of the rocker arms, it was difficult to mount a roller on the arm both because of the added space required for the roller and because of the problems involved in suitably supporting the roller in the rocker arm.

The present rocker arm construction is designed to eliminate these difficulties and provide a rocker arm construction having an adequately supported roller arranged so that the rocker arms herein disclosed may be substituted for the rocker arms heretofore employed without making any change whatsoever in the general layout of the engine. To this end, each rocker arm (see Figs. 3 and 4) comprises an arm member 20 provided at one end with a hub portion 21. Each hub portion 21 has a pair of bearing bushings 22 (see Fig. 4) mounted on the shaft 13 and extending inwardly from each end of the hub 21 with their inner ends spaced as at 23. The arm member 20 connects with its hub portion 21 adjacent one end of the latter, as is apparent in Fig. 4, and extends from the upper side of the hub portion 21, as is apparent in Fig. 3. The arm member 20 extends transversely to the shaft 13 by which it is carried and toward the opposite shaft 13. Each arm member 20 is thus pivotally supported on a shaft 13 and extends into the space between the two shafts. At its free end, each arm member 20 is provided with an adjustable tappet 24 threaded therein, the tappet being provided with a ball and socket connection with a valve actuating member 25.

From an inspection of Fig. 4, it will be noted that the arm members 20 of adjacent rocker arms are in a nested arrangement so that they can actuate the tappets 24 which are substantially in alignment transversely of the shafts 13.

The cam 15 for each rocker arm is positioned over the arm and located intermediate the ends of the latter. To provide for a roller in the arm to engage the cam 15, each arm member 20 is provided with a pair of spaced hub portions 30 intermediate its ends and thus providing a slot 31 extending vertically through the arm member 20. Mounted within the slot 31 is the cam-engaging roller, indicated at 32, the diameter of the roller 32 being preferably slightly greater than the diameter of the hub portions 30.

Because of the nested arrangement of the two arms of each pair, as shown in Fig. 4, and the proximity of the arms to the brackets 11 (see Fig. 1), no space is available for an axle for the roller, which protrudes beyond the side faces of the arm member. Any axle utilized for the roller thus must lie within the limit of the side faces of the arm member, that is, within the limit of the outer faces of the two hub portions 30. For this reason, I have provided an axle 33 (see Figs. 2 and 4) supported in the hub portions 30 and extending through the roller 32, the axle 33 having its end faces flush with the outer faces of the two hub portions 30. The roller 32 is rotatable relative to its axle 33 and preferably is provided with an internal bushing 34 mounted on the axle 33.

The axle 33 must, of course, be held in fixed relation to the arm member 20 so that it cannot shift relative thereto and, to this end, the axle is dimensioned so that it has a press fit within the hub portions 30. Such press fit alone would be insufficient, under the stresses to which it is subjected, to maintain the axle in proper position. A dowel pin 35 is therefore provided, extending radially in the axle and one of the hub portions 30 and having a press fit in the latter.

The dowel pin 35 similarly may be subjected to operational stresses and I, therefore, provide a means for retaining the dowel pin 35 in position. To this end, the axle is provided with an internal bore 36 and within the bore I insert a retaining pin 37 extending adjacent the inner end of the dowel pin 35 so as to prevent dislodgement of the latter. The retaining pin 37 is provided with a portion 38 dimensioned to have a press fit within the bore 36 of the axle so that it will be retained therein, and a reduced inner end 40 extending adjacent the inner end of the dowel pin 35.

The press fit of the axle within the hub portions 30 as well as the press fit of the dowel pin 35 within the hub portion may, of course, be sufficient in certain instances to prevent any shifting of either of these members. However, as a safety factor it is desirable to utilize the retaining means in the form of the pin 37 to prevent any chance of the dowel pin 35 shifting. So long as the dowel pin 35 remains in place, the axle 33, of course, is prevented from shifting longitudinally or rotatively relatively to the hub portions 30. The retaining pin 37 can never be subjected to any substantial operational stresses that might tend to dislodge it, since the only stresses that could be placed thereon would be due to a slight shifting of the dowel pin 35. However, the slight stresses resulting from any such shifting are transverse to the axis of the pin 37 and, therefore, would have no material tendency to cause the pin 37 to shift. The press fit of the portion 38 of the pin 37 thus is sufficient to retain the pin within the axle. The construction is, therefore, such that, while the dowel pin, which holds the axle against any shifting movement, is subjected to operational stresses, the retaining pin 37 is substantially free of stresses of this character so that the various parts of the assembly will remain in their proper relation.

The dowel pin 35 is adapted to be inserted through passages provided for supplying oil to the bearing surfaces between the roller bushing 34 and the axle 33. Thus, each shaft 13 is provided with an internal bore 41 connected to a source of oil under pressure. Within each hub portion 21, the shaft 33 is provided with a radial passage 42 leading to a longitudinally extending groove 43 in the periphery of the shaft 13. The groove 43 extends across the space 23 between the inner ends of the two bushings 22. Thus, oil is supplied not only to the bearing surfaces within the hub portion 21, but also to the space 23 between the two bushings 22.

Oil is adapted to be supplied to the bearing surfaces of the bushing 34 and axle 33 from the space 23. To this end, a drilled passage 44 extends lengthwise of the arm member 20 and tangentially intersects the space 23. The drilled passage 44 connects with a radial passage 45 formed in the axle 33 in alignment with the dowel pin 35. The passages 44 and 45 are somewhat larger than the dowel pin 35 so that the latter may be inserted through the passages 44 and 45 when assembling the dowel pin, axle and arm member. The outer end of the passage 44 may be closed by a threaded plug 46.

The bore 36 within the axle 33 is utilized as a portion of the oil passage and thus does not extend all the way through the axle 33 so that it leaves a closed end 50 therein. The other end of the bore 36 is closed by the enlarged portion 38 of the retaining pin 37. The reduced end 40 of the retaining pin 37 provides a closed annular space within the axle 33 in communication with

the oil passages 45 and 44. To connect this annular space with the bearing surfaces of the bushing 34 and axle 33, a radial passage 51 is provided in the axle 33 within the roller 32. The radial passage 51 extends to a longitudinal groove 52 provided in the periphery of the axle 33 and lying within the bushing 34. Thus, the various oil passages heretofore described provide a means for supplying oil to the roller and, at the same time, provide space for inserting the dowel pin 35 in the assembly of the parts.

It will be noted that the axle 33 has no head portion or the like which would protrude beyond the side faces of the hub portions 30. Thus, the entire assembly lies within the confines of the arm member 20 and, because of the dowel pin 35 and retainer pin 37, the axle will be adequately retained in its proper position. By so constructing the axle, it has a uniform diameter throughout its length. It thus may be finished on a centerless grinder, facilitating manufacture thereof.

From the foregoing description, it will be apparent that the rocker arm construction herein disclosed may be substituted for rocker arms heretofore employed without necessitating any changes whatever except those in the arm itself. The arm provides a rolling contact with the cam which eliminates wear heretofore encountered and provides a smoothly operating construction.

I claim:

1. A rocker arm construction of the character described comprising an arm member, a cam-engaging roller, an axle supporting said roller and extending transversely of said arm member with the ends of the axle lying within the limits of the side faces of said member, means for holding the axle against endwise and rotational movement relative to said member and subjected to operational stresses, and axially extending means in said axle mounted substantially free of operational stresses for preventing dislodgement of said first-mentioned means.

2. A rocker arm construction of the character described comprising an arm member having axially spaced hub portions, a cam-engaging roller positioned between said hub portions, a hollow axle mounted in said hub portions and supporting said roller, said axle and one of said hub portions having a radial oil passage, a dowel pin positioned diametrically opposite said oil passage and insertable therethrough, said dowel pin holding the axle against axial and rotational movement relative to said arm member, and means mounted in said axle for holding said dowel pin against dislodgement.

3. A rocker arm construction of the character described comprising an arm member having intermediate its ends a pair of axially spaced hub portions, a cam-engaging roller positioned between said hub portions, a hollow axle mounted in said hub portions and supporting said roller, said arm member and said axle having an oil passage extending longitudinally from one end of said arm member radially through one of said hub portions and said axle, a dowel pin positioned in alignment with said oil passage and insertable therethrough, said dowel pin extending through said axle and into said one hub portion to hold the axle against axial and rotational movement relative to said arm member, and means secured in said axle for preventing dislodgement of said dowel pin.

4. A rocker arm construction of the character described comprising an arm member having intermediate its ends a pair of axially spaced hub

portions, a cam-engaging roller positioned between said hub portions, a hollow axle mounted in said hub portions and supporting said roller, said axle being closed at one end and open at the other end, said arm member and said axle having an oil passage extending longitudinally from one end of said arm member radially through one hub portion and said axle adjacent the closed end of the latter, a dowel pin positioned in alignment with said oil passage and insertable therethrough, said dowel pin extending from the hollow interior of said axle radially outward and into said one hub portion, said axle having a second radial oil passage extending from the interior of the axle to said roller, and a retaining pin secured in and closing the open end of said axle and having a reduced inner end extending adjacent said dowel pin to prevent dislodgement thereof and providing an annular space within said axle connecting said oil passages.

5. A rocker arm construction of the character described comprising an arm member having intermediate its ends a pair of axially spaced hub portions and an oil passage extending from one end of said arm member into one of said hub portions, a cam-engaging roller positioned between said hub portions, a hollow axle mounted in said hub portions to support said roller and having a pair of oil passages connecting said roller with the oil passage in the arm member through the interior of said axle, means insertable through the oil passage in the arm and through one of said pair of oil passages for holding the axle against axial and rotational movement relative to the arm member, and means secured in the interior of said axle for preventing dislodgement of said first-mentioned means and shaped to provide space connecting said pair of oil passages in the axle.

6. A rocker arm construction of the character described comprising an elongated arm member having a bearing at one end adapted to be mounted on a rock shaft provided with oil supply passages, said arm member also having intermediate its ends a pair of spaced hub portions, a cam-engaging roller positioned between said hub portions, a hollow axle mounted in said hub portions and supporting said roller, said axle having oil passages for supplying oil to said roller, a dowel pin for holding the axle against axial and rotational movement relative to said hub portions, and means secured in said axle for preventing dislodgement of said dowel pin, said arm member having a longitudinal oil passage extending tangentially from said bearing to receive oil therefrom and into one of said hub portions to connect with the oil passages in said axle, said dowel pin being insertable through said longitudinal passage.

7. A rocker arm construction of the character described comprising an arm member having an end portion provided with a bearing adapted to be mounted on a rock shaft and having a pair of spaced hub portions with an oil passage connecting said bearing with one of said hub portions, a cam-engaging roller positioned between said hub portions, an axle carrying said roller and mounted in said hub portions and having an oil passage comprising axially and radially extending portions connecting the oil passage in the arm with said roller, means insertable through the oil passage in the arm and through a radially extending portion of the passage in the axle and into said one hub portion for holding the axle against axial and rotational movement, and

means secured in the axially extending portion of the oil passage in the axle for preventing dislodgement of said first-mentioned means.

8. A rocker arm construction of the character described comprising an arm member having a pair of spaced hub portions and an oil passage leading to one hub portion, an axle extending from one hub portion to the other, a cam-engaging roller rotatably mounted on said axle between said hub portions, said axle having a longitudinally extending oil groove in its periphery underlying said roller and an oil passage connecting said groove with the oil passage in said arm member, means insertable through the oil passage in the arm member for holding the axle against axial and rotational movement relative to the arm member, and means secured in the oil passage in the axle to prevent dislodgement of said first-mentioned means, both of said means being shaped and positioned to permit free flow of oil through said passages to said groove.

9. A device of the character described comprising an arm member having a slot, a cam-engaging roller positioned within said slot, a hollow axle supporting said roller and extending transversely through said member with a press fit therein and with the ends of the axle flush with the side faces of the member, a dowel pin having a press fit in said member for holding the axle against endwise and rotational movement relative to said member, and a retaining pin mounted in said axle

substantially free of operational stresses for insuring against dislodgement of said dowel pin.

10. A device of the character described comprising an arm member having a slot, a cam-engaging roller positioned within said slot, a hollow axle supporting said roller and extending transversely through said member with a press fit therein and with the ends of the axle flush with the side faces of the member, a dowel pin having a press fit in said member for holding the axle against endwise and rotational movement relative to said member, and a retaining pin for said dowel pin mounted with a press fit in said axle, said retaining pin extending transversely to said dowel pin and being mounted in said axle so as to be substantially free of operational stresses.
